UNITED STATES PATENT OFFICE.

FRANK A. LUNDQUIST, OF CHICAGO, ILLINOIS, ASSIGNOR, BY MESNE ASSIGNMENTS,
TO WESTERN ELECTRIC COMPANY, A CORPORATION OF ILLINOIS.

SWITCHING MECHANISM FOR TELEPHONE-EXCHANGES.

1,081,128.

Specification of Letters Patent.

Patented Dec. 9, 1913.

Application filed February 1, 1905. Serial No. 243,664.

To all whom it may concern:

Be it known that I, FRANK A. LUNDQUIST, a citizen of the United States of America, and a resident of Chicago, county of Cook, and State of Illinois, have invented certain new and useful Improvements in Switching Mechanisms for Telephone-Exchanges, of which the following is a specification.

My invention relates to switching mechanisms for automatic telephone exchanges and has for its object improvement and simplification of such devices.

The present device is especially adapted for use in the kind of exchanges illustrated in my Patent No. 773,524 issued Dec. 6, 1904, but its use involves a modification in the preliminary part of the arrangement. In that patent I showed main switches and auxiliary switches. There was a main switch for each subscriber, and each main switch had one hundred pairs of contact points. This made the switches which were individual for each subscriber large and expensive.

The ultimate object of the device of the present application is to substitute for one hundred such large switches, in the kind of exchange indicated, one hundred small switches each having ten or twelve pairs of contact points, and ten or twelve large switches. The present application is limited to this small switch and its operation.

In the accompanying drawings Figures 1, 2 and 3 are respectively front, side and rear elevations of the individual switches mentioned; Fig. 4 is a diagram of the mechanical operation; Fig. 5 is a partial electrical diagram showing the automatic operation; Fig. 6 is a complete electrical diagram; Fig. 7 is a section on line 7—7 of Fig. 1; and Fig. 8 is a section on line 8—8 of Fig. 1.

The switch consists of a pair of contact makers P and P¹ insulated from each other, and moved over corresponding sets of contact points P² and P³ by means of a ratchet wheel F. These contact points are insulatingly held between a plate P⁴ and a bracket P⁵ (Figs. 2 and 8) secured to a bridge D² between the side plates D. There is a magnet A for moving the wheel, and a relay a is associated with A so that when the switch is started into operation by an impulse controlled from the subscriber's station, the movement automatically continues until it is stopped by an impulse automatically sent

through a magnet B. A magnet C and its relay c serve to release the switch so that it may return to its normal position in the ordinary manner.

Referring to Fig. 4, when the armature A¹ is actuated by the magnet A the pawl A² advances the wheel F on which the contact makers P and P¹ are carried as before mentioned. A holding pawl E prevents a backward movement of the wheel F until it is released. The pawl A² has a tail piece A³ which normally engages a pin A⁴ and is thereby held clear of the wheel F so as not to prevent its release. This mechanism, and that hereafter to be described, is held by, and largely between, two side plates D, which side plates are connected together by bridges D¹. The different parts are secured by screws either to the side plates or to the bridges, or to brackets connected to the plates or bridges. The upper ends of the side plates have at the rear upwardly projecting portions D⁴ (Fig. 2) which are arranged to fit into suitable sockets in a framework intended to support a series of similar switches. Secured in a block of insulation D⁵, held between the lower ends of the side plates, are a series of springs D⁶, each of which is adapted to make electrical connection with a fixed contact on the framework for holding a series of switches. These things are matters of convenience in the setting up and taking down of switches located in an exchange. As the operation of the mechanism can be better understood by diagrammatic views than otherwise, reference will be had principally to Figs. 4, 5 and 6, which are diagrammatic representations of the mechanism shown in Figs. 1, 2, 3, 7 and 8.

When an impulse flows through magnet B, the armature B¹ engages a hook on the bar B², and when the armature is released its retractile spring draws down the bar B². On the upper end of the bar B² is a piece of insulation B³, the office of which is to shift the electrical connections of the adjacent springs when said bar is depressed by armature B¹. These springs are shown as lying in a horizontal position at the tops of Figs. 1, 2 and 3. As will be hereinafter explained, this action breaks the circuit for the magnet A and stops the automatic advance of the switch.

The magnet C is used for release. Its ar-

mature lever C^1 has mounted on its end a bell crank lever C^2 , one end of which is provided with a hook adapted to engage an arm E^1 secured to the holding pawl E , and the other end of which is adapted to engage a stationary pin C^3 . The joint between C^1 and C^2 is a friction joint so that C^2 naturally stays in the position into which it is put by force.

- 10 When an impulse flows through C and the armature C^1 is attracted, the bell crank C^2 strikes the pin C^3 and forces the hook on C^2 behind the arm E^1 . When the circuit is broken through C , and the retractile spring 15 returns C^2 to its normal position, the hook draws the arm E^1 inward releasing the holding pawl E from the wheel F . At the same time the other end of the arm E^1 engages the bar B^2 so as to release it from the armature B^1 , thus permitting B^3 and the adjacent 20 springs to resume their normal position. The ratchet wheel F and contact makers P^1 and P are secured to a shaft F^2 (Figs. 1, 2 and 8), and also secured to the same shaft is 25 an ordinary clock spring located in a spring case F^3 . The release of the holding pawl E (Fig. 4) from the wheel F permits the spring in the case F^3 to return the contact makers to their normal position. When the 30 next operating impulse flows through A its armature strikes the bell crank C^2 and releases its hook from E^1 so that the holding pawl may again engage the ratchet wheel F .

Each switch of this kind in the exchange 35 is connected to a subscriber's station by wires 4 and 39 as shown in Fig. 6. Both the switch and the station have ground connections. When a subscriber wishes to start his switch into automatic operation he temporarily 40 closes the connection between his end of the line 4 and ground. A current then flows: $X-1-2-a-3-4$ station-ground-X. This operates the magnet a and causes its armature 13 to connect to spring 12. A 45 current then flows: $X-1-2-A-5-6-7-8-9-10-11-12-13-14-X$.

This circuit is shown in Fig. 6. As the automatic operation now to be described can be better understood by separating it 50 from other things, reference may be had to Fig. 5, which figure is especially designed to illustrate this operation.

When the impulse flows through A it advances the ratchet wheel F and moves F^1 55 away from 17 permitting 17 to close connections to 16. The movement of the armature A^1 also breaks electrical connection at 20 and at 30.

The operations so far described are the 60 direct result of the circuit closed by the subscriber at his station. As soon as he breaks this circuit the armature 13 of the relay a falls back and breaks the connection to 12. This breaks the circuit for A , and when the 65 armature A^1 falls back it closes a new cir-

cuit for a as follows: $X-1-2-a-3-4-16-17-18-19-20-21-22-23-24-25-14-X$. This again closes the circuit for A at 12 and causes a new movement of A^1 . This new movement of A^1 70 again breaks the circuit for a at 20. But the current must not cease flowing through a until A^1 has completed its movement otherwise that movement never would be completed because breaking the circuit through 75 the relay immediately causes a break of the circuit through the operating magnet. To prevent the current being stopped too soon through the relay, the armature 13 closes a branch as follows: from 4-26-27-28-29-30-22-etc. This is held until at the final part of the movement of the armature 80 A^1 , the circuit for the relay a is broken at 30. This break permits the armature 13 to fall back and break the circuit for A at 12. 85 This in turn permits the armature A^1 to also fall back to its normal position, in which position it again closes the circuit for the relay. It will be seen from this that the 90 closure of a preliminary circuit for the relay by the subscriber causes the relay to close a circuit for the operating magnet, and thus in turn to cause a movement of the switching mechanism. Nothing further then occurs until the subscriber breaks the 95 circuit he has closed when the relay in turn breaks the circuit for the operating magnet. Nothing electrical then occurs until the armature of the operating magnet has reached 100 its normal position when it closes a new circuit for the relay. This again causes the relay to close the circuit once more for the operating magnet. The operating magnet in turn breaks the circuit for the relay but does not do so until it completes its movement. The relay immediately breaks the 105 circuit for the operating magnet, the armature of the latter falling back almost simultaneously with that of the relay. When the armature of the operating magnet again reaches its normal position it again closes 110 the circuit for the relay thus starting a second cycle of automatic operation.

In still more condensed language, we may say, that the subscriber makes and breaks a 115 circuit the result of which is to cause one complete operation of a relay and the magnet associated therewith. Upon the completion of this operation the magnet starts a series of interacting makes and breaks with 120 the relay, the two being so related that each causes the other to operate, the successive operations being continuous until stopped by some outside force.

Each time that the armature A^1 is actuated 125 it advances the contact makers, (or wipers as they are commonly called) P and P^1 over their respective contact points. At its advanced position the armature A^1 also closes connection between 32 and 33. When 130

the wiper P^1 in advancing over its contact points reaches a point which is connected by wire to an idle switch, as set forth in my Patent No. 776,524, then a current flows: 5 $X-1-2-31-32-33-34-B-35-P^1$ — a contact point P^2 — from which point it flows over the line through the idle switch and eventually reaches ground and returns to battery X . This current actuates B and 10 causes B^3 to be depressed so as to break the circuits for A at 7 and 23. The depression of B^3 also closes 37 to 36, and 41 to 40. Breaking the circuit for A brings the wipers P and P^1 to a stop on contact points having 15 connections to the automatically selected switch. For a full understanding of matters beyond what is herein shown and described reference may be had to my previously mentioned Patent No. 776,524. With 20 his switch in this position, the subscriber may, by closing either line 4 or line 39 to ground, complete a circuit through his switch to the selected switch, and thence to a ground connection which the selected 25 switch is presumed to have. Thus the line 4 extends to 36-37-38- P^1 and out to the next switch. The line 39 extends to 40-41-42- P and out.

There is a branch from line 4 so that 30 when that line is closed to ground it operates the relay a as before described, but this operation is without effect after the circuit for A is broken unless the line 39 is simultaneously closed to ground.

35 In that event the connection between 44 and 45 closed by the armature 13 completes a circuit from the relay c as follows: $X-1-2-43-44-45-46-c-47-39$ —station—ground— X . This operates the armature of c and closes 50 to 49 when a current flows: $X-48-O-49-50-51-14-X$. This is a circuit through the release magnet C and causes the switch to return to its normal position as before described.

45 The manner in which the essential elements of this switch are arranged into a concrete machine is immaterial to the present consideration. Figs. 1, 2, and 3 illustrate at full size a convenient arrangement 50 which I have used for the purpose. I have placed reference characters on the principal parts of these drawings so that it may be readily seen in what manner I have chosen to put them together. For the minor 55 parts reference characters are omitted from these views as tending to confuse rather than illustrate the arrangement. From Figs. 4, 5 and 6, and the description thereof, the mechanic can readily construct a switch 60 in such form as he chooses, or he can make a practical reproduction of the arrangement shown in Figs. 1, 2 and 3.

What I claim is:—

1. The combination with two magnets arranged to act as relays for each other so as

to produce a continuous motion, and a battery provided with connections to said magnets, of a circuit finding contact maker moved by one of said magnets, a third magnet provided with connections to said battery and said contact maker, means by which upon said contact maker finding a circuit an impulse will flow through said third magnet to cause its operation, and means by which the operation of the third magnet will stop the operation of the first two magnets. 70

2. The combination with two magnets, and means by which they keep each other in continuous operation, of a circuit finding contact maker moved by one of said magnets, a third magnet arranged to have its circuit closed by said contact maker, and means by which upon said contact maker closing such circuit, the operation of the 85 third magnet will stop the operation of the first two magnets.

3. The combination with a battery, two magnets, and connections for said magnets so arranged that upon an initial movement 90 being given to one of said magnets the two will start upon an automatically continuous series of operations, of a circuit finding contact maker operated by one of said magnets, a third magnet connected in an incomplete 95 circuit, means by which the contact maker will complete the circuit for the third magnet so as to cause its operation, and means by which the operation of the third magnet will stop the automatic operation of the first 100 mentioned magnet.

4. The combination with a contact maker, and a pair of interacting magnets arranged to automatically advance said contact maker step by step, of a series of contact points in 105 the path of said contact maker, some of which points represent busy lines and some of which represent idle lines, of automatically operating means by which the automatic advance of said contact maker is 110 stopped when said contact maker comes into contact with a point representing an idle line.

5. The combination with a contact maker, and a pair of interacting magnets arranged 115 to automatically advance said contact maker step by step, of a battery provided with a connection to said contact maker, a series of contact points in the path of said contact any one of which may serve as a path for an 120 impulse from said battery, and automatically operating means for stopping said magnets when an impulse flows from said battery, through one of said points.

6. The combination with a series of contact points representing idle and busy lines, a contact maker arranged so that when moved it will engage said contact points in succession, and a battery provided with an 125 electrical connection to said contact maker, 130

4
of a pair of interacting magnets arranged to automatically advance said contact maker over said contact points, means by which upon said contact maker engaging a point representing an idle line, an impulse will flow from said battery through said point, a third magnet operated by such an impulse, and means by which an operation of the third magnet will stop the operation of the first mentioned magnets.

10 7. The combination with a battery, two magnets, and connections for said magnets so arranged that upon an initial movement being given to one of said magnets the two 15 of them will start upon an automatically continuous series of operations, of a circuit finding contact maker operated by one of said magnets, a third magnet connected in an incomplete circuit for said third magnet, and means by which the operation of said 20 third magnet will stop the automatic operations of the first mentioned magnets.

8. The combination with a battery, two magnets, and connections for said magnets 25 so arranged that upon an initial movement being given to one of said magnets the two 20 of them will start upon an automatically continuous series of operations, of a circuit finding contact maker moved step by step 30 by the operations of one of said magnets, a third magnet connected in an incomplete circuit for said third magnet, means by which said contact maker may complete the circuit for said third magnet through any one of a 35 series of contacts touched by it in its step by step movement, and means by which an operation of the third magnet will stop the automatic operations of the first mentioned magnets.

40 9. The combination with a circuit finder and a circuit breaker, of two magnets for automatically operating the circuit finder, a third magnet for operating the circuit breaker, means by which the circuit finder 45 completes a circuit through the circuit breaker by way of some one of a plurality of paths, and means by which the operation of the circuit breaker stops the operation of the circuit finder.

50 10. In a trunk selecting switch, a pair of wipers and a single row of contact points for each wiper, a pair of magnets arranged to automatically advance said wipers over their contact points to find an idle trunk, 55 and automatically operating means controlled by an impulse flowing over a found trunk for stopping said wipers.

11. The combination with a switching mechanism comprising a pair of wipers and 60 a single row of contact points for each wiper, said rows of contact points being in line with the movements of said wipers, of two magnets arranged to be started into operation by an impulse sent through one of 65 them and also arranged to keep each other

in continuous operation to advance said wipers to find an idle pair of contact points in said rows of points, and automatic means operating through one of the found points for stopping the operation of said magnets. 70

12. The combination with two magnets arranged to act as relays for each other so as to keep each other in continuous operation, a circuit finding contact maker operated thereby; and a series of circuits successively 75 engaged by said contact maker, of a third magnet arranged to have its circuit closed by said contact maker through an idle one of said circuits, and means by which an operation of the third magnet will interrupt 80 the interacting operation of the first mentioned magnets.

13. The combination with a series of circuits, a magnet adapted to be operated by an impulse flowing over any one of said circuits, and a circuit finder adapted to complete connections for said magnet over an idle one of said circuits, of automatically operating means consisting of a second magnet and an associated relay; for moving 90 said circuit finder from circuit to circuit in said series of circuits, and means by which an operation of said first named magnet causes a stoppage of said circuit finder on a found idle circuit. 95

14. The combination with a series of circuits, a magnet adapted to be operated by an impulse flowing over any one of said circuits, and a circuit finder adapted to complete connections for said magnet over an idle 100 one of said circuits, of other magnets and a source of electric current arranged to automatically move said circuit finder from circuit to circuit in said series of circuits, and means by which an operation of the first 105 mentioned magnet will disconnect the last mentioned magnets from the source of current to cause a stoppage of the circuit finder on a found idle circuit.

15. The combination with a ratchet wheel, 110 a magnet and pawl for driving it, and a holding pawl, of wipers carried by said wheel, a telephone line normally disconnected from said wipers, a magnet for automatically connecting the telephone line to 115 the wipers upon actuation, and a release magnet arranged to simultaneously release said holding pawl from said wheel and said line from said wipers.

16. A switch provided with contact 120 makers adapted to make contact in succession with contact points representing idle and busy trunks, a magnet and devices associated therewith for automatically advancing said switch step-by-step upon the 125 reception of an initiatory electrical impulse, a pair of subscriber's lines terminating in disconnected contact springs, other adjacent contact springs provided with connections to said magnet and said wipers, and a 130

second magnet controlled through one of
said wipers and a contact point represent-
ing an idle line for shifting the last named
contact springs so as to interrupt the op-
eration of the first named magnet and to
5 extend the connections of the subscriber's
lines to said wipers.

Signed at Chicago, Ill. this 28th day of
Jan. 1905.
